UNITED STATES PATENT OFFICE.

FREDERICK WILLIAM McNABB, OF PARRY SOUND, CANADA.

WRENCH.

SPECIFICATION forming part of Letters Patent No. 779,301, dated January 3, 1905.

Application filed July 2, 1904. Serial No. 215,125.

To all whom it may concern:

Be it known that I, FREDERICK WILLIAM McNABB, a subject of the King of Great Britain, and a resident of Parry Sound, in the Province 5 of Ontario, Dominion of Canada, have invented a new and Improved Wrench, of which the following is a full, clear, and exact description.

My invention relates to a wrench capable of 10 many uses, but especially adapted for use on pipes and the like, its main objects being to secure a maximum efficiency in devices of this character without increasing the cost or causing any undesirable complication.

15 Other objects are to prevent slipping of the instrument and injury to the pipes or other articles on which it is to be used and to provide for wide adjustments and the like.

20 Further objects will be mentioned in the course of this specification.

Reference is to be had to the accompanying drawings, forming a part of this specification, in which similar characters of reference indicate corresponding parts in all the figures.

25 Figure 1 is a side elevation, partly in section, showing a preferred form of my invention. Fig. 2 is a plan view thereof. Fig. 3 is an end elevation. Fig. 4 is a sectional view on the line 4 4 of Fig. 1, and Fig. 5 is a fragmentary plan view showing the construction of a chain which I prefer to employ.

30 *a* represents the body of the instrument, and *b* the handle, which is secured to the body by means of a screw-threaded portion *b'* for the purpose of making the handle removable from the body. A chain *c* is attached to the lower side of the front end of the instrument, as shown at *a'*. This chain may be of any desired construction; but it is shown as being provided with projections *c'* for the purpose of securing it in the desired position with respect to the main body of the instrument.

35 *d* is an element secured to the body *a* in any desired manner—for example, by means of bolts *d'*. It is provided with projections *d'* near the center of the body of the instrument and with a cross-piece *d''*, which extends from one side of the body *a* to the other and arrests motion of the element *d* toward the body *a*. On the rear side of the projections

40 *d'* is a slot *d'''* for the reception of the projections *c'* above mentioned. For convenience both of these projections *d'* have a slot *d''*, the chain also being provided with projections *c'* on both sides thereof. The chain 55 may be passed around a pipe *X*, as shown in Fig. 1, and extended rearwardly, so that the pair of projections *c'* engage in a pair of slots *d'''*, and the pipe will be contained within the chain and will come into contact with the 60 front end *a''* of the body of the instrument. In order to provide for securely holding the pipe in position, projections extending from the body of the instrument are provided. These projections are shown as taking the 65 form of integral extensions *d''* upon the element *d*, which are shown as being curved from the side of the instrument to which the chain is attached at *a'*. These projections are also provided with teeth or serrations *d''* for 70 the purpose of more securely holding the pipe or other article upon which the wrench is designed to be used.

75 It will be obvious that this wrench can be adjusted to any position by removing the projections *c'* from the slots *d'''* and putting other projections upon the chain in that position. It will also be obvious that a secure grip is furnished and that in the use of the device it will not slip upon the pipe.

80 While a particular form of my invention has been illustrated and described, it will be obvious that it may take other forms and that it is not strictly limited to the embodiment represented in the drawings and described in 85 this specification.

Having thus described my invention, I claim as new and desire to secure by Letters Patent—

1. A pipe-wrench comprising a body having a flat front end, a chain having an end secured to the body at one side thereof and provided with projecting studs, a curved bar extending from said body at the other side thereof, the front end of the body constituting means for engaging with a pipe when placed 90 in the wrench, and a projection upon said bar at the opposite side from that at which the chain is attached to the body, said projection having depressions for the reception of said studs.

2. A wrench comprising a body, a chain having an end secured to the body at one side thereof and provided with studs, a pair of arc-shaped bars projecting from two sides of said body and curving away from the side at which the chain is attached and provided with teeth or serrations upon their front convex surfaces, said bars being provided with a pair of projections, each of said projections extending away from the body and having a depression in its rear edge for the reception of the studs on said chain, and a cross-bar connecting said bars and resting on the upper surface of said body to hold the bars against upward motion at their outer ends.

3. A pipe-wrench, comprising a body having a flat front end, a chain having an end secured to the body at a point below and at the rear of said end, said chain being provided with studs projecting from it upon opposite sides, a pair of arc-shaped bars projecting from two sides of said body at the upper por-

tion thereof and curving upwardly upon the arc of a circle, said bars having teeth upon their convex surfaces, the space between said bars and the bottom of said body which contains the said front end of the body constituting means for engaging with a pipe when placed in the wrench, said bars each being provided with a projection extending away from the body and having a depression in its rear edge for the reception of the studs on said chain, and a cross-bar connecting said bars and resting on the upper surface of said body to hold the bars against upward motion at their outer ends, said bars being secured to the body at a point near the front end thereof.

In testimony whereof I have signed my name to this specification in the presence of two subscribing witnesses.

FREDERICK WILLIAM McNABB.
